UNITED STATES PATENT OFFICE.

WILLIAM H. VINCENT, OF PARK SIDE, SOUTH AUSTRALIA, AUSTRALIA.

COOK-STOVE ATTACHMENT FOR GAS-JETS.

1,345,295.

Specification of Letters Patent. Patented June 29, 1920.

Application filed November 26, 1918. Serial No. 264,267.

To all whom it may concern:

Be it known that I, WILLIAM H. VINCENT, a citizen of Australia, residing at Park Side, South Australia, Australia, have invented 5 certain new and useful Improvements in Cook-Stove Attachments for Gas-Jets, of which the following is a specification.

This invention relates to an improved cooking stove, and more particularly to one 10 adapted to be employed as an attachment to a gas jet, whereby when owing to limited space, it is not convenient or possible to use an ordinary gas range owing to the space taken up by the same, an attachment in accordance with the invention, may be associated with a gas burner, so as to provide a 15 cooking stove, with an oven and gas burner, so that one can bake, boil or cook in any fashion desired.

20 A further object of the invention is to provide a novel construction of cook stove for the purposes specified and also a novel arrangement of supports for the same, adapting the device to be positioned over a gas 25 burner as specified.

With the above objects and others in view, as will appear as the description proceeds, the invention consists of the various novel 30 features of construction, combination of elements and arrangement of parts which will be more fully described herein and set forth with particularity in the claim appended hereto.

Reference is had to the drawings forming 35 a part of the application, in which—

Figure 1 is a plan view of my improved 40 stove attachment for gas burners,

Fig. 2 is a transverse sectional view of the same,

Fig. 3 is a sectional view taken at right angles to Fig. 2, and showing the supporting structure for the stove, and

Fig. 4 is an enlarged detailed sectional view showing the manner of applying the 45 stove to the gas burner pipe or tip.

Referring to the drawings in detail, the 50 numeral 10 designates a wall or other vertical support, from which projects horizontally, a gas pipe 11 in the form of a fixture having the usual form of valve 12 leading to the burner 13.

The stove generally designated at 14, is 55 adapted for application to the burner 13 and comprises a sheet metal oven-like arrangement including a back wall 15 having an opening 16 for the escape of excess heat and

vapors, while a door 17 is provided at the front thereof. The oven also has the inner end wall 18 adjacent to the wall or support 10, an outer wall 19 and top 20, while the 60 bottom portion 21 serves as means for attachment of a right angular bracket 22 having horizontal and vertical portions connected to the wall and to the bottom portion of the oven respectively, as shown at 23. 65 Diagonal braces 24 are also provided between the vertical and horizontal portions of the brackets 22, thereby providing a rigid supporting structure in combination with a plurality of right angular brackets 25 connected to the wall and top wall or portion 70 20 of the oven.

Arranged upon the top wall 20 is a gas ring or burner 26 supported by a series of brackets or lugs 27 spaced from the top portion 20 and receiving thereunder, a branch supply pipe 28 for gas connected to the burner pipe 11 through the medium of a T-joint shown at 29, the pipe 28 extending upwardly adjacent to the side wall 18 of 80 the stove and inwardly under the frame 30 having top and bottom inwardly extending edge flanges 30' and 30'' respectively positioned around the top portion 20 and provided with parallel bars 31 disposed on the 85 top flange 30' and retained in position by a supplementary frame 31' providing means whereby to support one or more cooking utensils over the burner 26.

Arranged within the oven are series of 90 shelf holders 32 designed to support one or more shelves 33 upon which suitable cooking utensils may be arranged for baking purposes. The burner for supplying heat to the ovens, consists of a pipe 34 arranged longitudinally beneath the oven or bottom 21 thereof at right angles to the wall, and having a depending portion 35 intermediately of its ends to engage the burner 13 as clearly shown in Fig. 4 of the drawings. The 100 burner is provided with a reduced portion 36 forming a shoulder 37 to receive the depending portion 35 thereagainst, so as to form a gas tight connection and the free end of the pipe 34 has air ports 34' and extends 105 upwardly as shown at 36 through the bottom wall 21, and then rearwardly toward the back wall 15, as shown at 39. The horizontal portions 39 lead centrally into the burner pipe or elongated burners 40 having 110 the usual apertured burner projections 41 through which the gas issues and is ignited.

The supply of gas to the burners 40 is controlled by the valve 12, while a valve 42 in the pipe 28 serves to control the flow of gas to the burner 26 as is clearly shown in Fig. 3 of the drawings.

From the foregoing description taken in connection with the accompanying drawings, it is thought that a clear and comprehensive understanding of the construction, 10 operation and advantages of my invention may be had.

Having thus described my invention, what I claim as new, and desire to secure by Letters Patent of the United States, is:

15 A cooking stove comprising a casing forming an oven accessible through its front, a

substantially U-shaped pipe forming a stem with branches passed through the bottom of the oven and extended laterally for a distance therein, burner tubes interiorly of the oven at opposite sides thereof and connected with the lateral extensions of said branches, the stem of said pipe having openings for introducing air and being adapted to detachably telescope over a gas jet burner and 20 abut the flanged portion thereof, and a burner ring exteriorly of and upon the top of the oven and having a valved lead for connection with the pipe leading to gas jet.

In testimony whereof, I affix my signature hereto.

WILLIAM H. VINCENT.
